FIG. 1.

FIG. 2.

INVENTOR

BY LAWRENCE GIANERA
Hazard & Miller

ATT'YS.

UNITED STATES PATENT OFFICE.

LAWRENCE GIANERA, OF LOS ANGELES, CALIFORNIA.

DESIGN FOR A BEAD FOR ORNAMENTAL NECK CHAINS.

61,134.

Specification for Design. Patented June 27, 1922.

Application filed January 12, 1922. Serial No. 183. Term of patent 3½ years.

To all whom it may concern:

Be it known that I, LAWRENCE GIANERA, am a citizen of the United States, residing at Los Angeles, in the county of Los Angeles, and State of California, and have invented a new, original, and ornamental Design for Beads for ornamental neck chains, of which the following is a specification, reference being had to the accompanying drawing, forming part thereof.

Figure 1 is a top plan view of a bead for ornamental neck chains.

Figure 2 is a cross-section taken on line 2—2 Figure 1.

I claim:

The ornamental design for a bead for ornamental neck chains, as shown.

LAWRENCE GIANERA.
